UNITED STATES PATENT OFFICE.

LOUIS M. HOOPER, OF RUTHERFORD, NEW JERSEY, ASSIGNOR TO THE J. L. MOTT IRON WORKS, A CORPORATION OF NEW YORK.

WATER-CLOSET.

1,202,524.

Specification of Letters Patent. Patented Oct. 24, 1916.

Application filed January 27, 1913. Serial No. 744,371.

To all whom it may concern:

Be it known that I, LOUIS M. HOOPER, a citizen of the United States, residing at Rutherford, in the county of Essex and 5 State of New Jersey, have invented certain new and useful Improvements in Water-Closets, of which the following is a specification.

My invention relates to new and useful 10 improvements in water closets of that character or type in which the bowl or receptacle is supported free from the floor.

The invention particularly contemplates the provision of an improved support or 15 anchorage for the bowl or receptacle which will support the latter free from the floor, which support or anchorage will be supported by the floor and be so constructed that a free space is afforded between the bot- 20 tom of the bowl and the floor.

The invention is particularly, although not solely, applicable to that type of closet having a substantially vertical rear portion adapted to engage and be connected to a 25 supporting means, an example of which closet is the well-known form of wall-closet, the rear vertical portion of which is adapted to be secured adjacent to a wall, or other vertical element, so that the bowl projects 30 therefrom, but is free of the floor located in advance of said vertical portion, wall, or element.

The primary object of the invention is to provide a support or anchorage, which will 35 so sustain the bowl as to relieve the soil-pipe, or other pipe connections therewith, of the weight of the bowl or strains to which it may be subjected in use, and which will permit expansion, contraction, or other 40 movement of the pipes, or of the bowl, without derangement of the related parts. This is particularly advantageous in the case of wall closets inasmuch as injury to a wall, or its equivalent, or other vertical member, is 45 prevented, due to any movement of the bowl or the soil-pipe relative to each other.

The invention consists in the construction and improvements to be more fully described hereinafter, and the novelty of 50 which will be particularly pointed out and distinctly claimed.

I have fully and clearly illustrated the invention in the accompanying drawings to

be taken as a part of this specification, and wherein:

Figure 1 is a perspective view of a wall closet construction including my invention; Fig. 2 is a view of vertical section through a wall showing a wall closet construction and arrangement, including my invention, the support and closet bowl being shown partly in vertical section; Fig. 3 is a view similar to Fig. 2 showing another embodiment of the same invention; Fig. 4 is a view in side elevation of another support embodying my invention.

Referring to the drawings by characters of reference, 1 designates a closet bowl of a type well known in the construction of wall closets, the same including a seat receptacle 2, provided at its rear with a vertical part or face 3 having vertical securing flanges 4, 4 projecting laterally therefrom, said part 3 and the flanges being adapted to rest in engagement with a vertical member or wall 5, see Figs. 2 and 3, when the bowl is installed. The vertical part 3 is also provided with a rearwardly projecting surrounding flange 6, whereby the rear part of the bowl is recessed as shown. At the rear, within the said recess, the bowl is provided with the usual outlet 7, surrounded by a rearwardly projecting flange 8, about which is seated a coupling collar 9, to which is connected a coupling pipe 10, preferably of lead to give the desired flexibility as herein-after set forth, the rear end of said pipe 10, being connected by a wipe joint 11 to a brass ferrule 12, connected to the branch coupling 13 of a soil pipe 14.

I will now describe the support by means of which the bowl above described is supported so that the weight thereof does not rest on the soil pipe, and the latter may expand and contract without affecting the bowl and its attaching means, referring particularly to Figs. 1 and 2 of the drawings.

15 designates a base member adapted to be anchored in a floor or rest upon the supporting beams of a floor, said member being shown as substantially horizontal. Rising from this base member 15, is a substantially vertical supporting member 16, adapted to be embedded in the wall structure from which the bowl projects, said member 16 being bifurcated to provide vertically spaced

arms 17, separated by a space through which the pipe 10 may pass when the bowl is installed. These arms 17 may be, and preferably are, provided with forwardly projecting upper portions 18, which, when the installation is made, project slightly beyond the face of the wall, into the recessed back of the bowl and are secured to the bowl by bolts 19 let through openings in the flanges 10 and screwed into openings in the said projecting portions 18. The arms 17 are preferably so proportioned that the upper ends thereof will come closely adjacent the upper cross flange 6, and the outer side edges thereof will abut the inner faces of the vertical parts of said flange 6, so that a rigid arrangement is provided. The part 16 and the arms 17 are so arranged that when the support is in position to support the bowl 20 the part 16 will be located within the finished wall and the outer vertical faces 17 of the arms 17 will be substantially flush with the surface of the wall, so as to provide a rigid surface against which the bowl is secured and held.

In the embodiment shown in Fig. 3 the same objects are sought and obtained, the difference over the form shown in Figs. 1 and 2 being that in Fig. 3 the base piece, instead of being arranged to project forward beneath the bowl and under the floor, is directed rearward as at 20 and adapted to be seated in the wall structure, the base being held rigidly in place by the bricks, stone or other elements comprising the wall. As far as the parts adapted to be secured to the bowl are concerned, they are the same as shown in Figs. 1 and 2.

In Fig. 4 a further embodiment is shown, in which the base member may include a part 21 extending forward from the wall similar to the part 15 in Figs. 1 and 2, and a part 22, extending rearward from the part 16, similar to the part 20 in Fig. 3.

When the parts are installed, the base 15 is covered by the floor surfacing material as shown in Fig. 2, and the part 16, is covered by the wall surfacing material such as plaster, tiling or whatever might be employed for that purpose, so that the support is not visible in the complete structure.

It will be noted that in all of the forms described I provide an anchorage and support which is entirely concealed when the parts are assembled, which supports the bowl entirely independently of the soil pipe, so that the latter, by virtue of its flexible connection with the bowl, is free to expand and contract lengthwise under changes of temperature without in any way tending to move the bowl or its fastenings. The fact that the bowl and its fastenings are not moved by the expansion and contraction of the soil pipe is important because the loosening and cracking of the plaster or tiling ad-

acent the bowl and its fastening devices is prevented.

The support in all the forms shown and described is preferably, although not necessarily, made in one piece, of substantial rigid metal, so that it will not be bent or sprung by the weight of the bowl, or the weight to which the bowl is subjected.

The base piece may be provided with openings 23, as shown in Fig. 1, to receive securing bolts, for securing it in place on a structural beam, as shown, or to such other fastening devices as the nature of the situation may require.

What I claim and desire to secure by United States Letters Patent is:

1. A closet bowl support comprising a horizontal member adapted to be supported by a floor structure, and a vertically extending supporting member rigid with said horizontal member, and adapted to take position in rear of a closet bowl, said supporting member having arms spaced apart to provide an opening for passage of a pipe to the closet bowl.

2. A closet bowl support comprising a horizontal member adapted to be supported by a floor structure, and an upwardly extending supporting member rigid with said horizontal member and adapted to take a position in rear of a closet bowl, and having an opening therethrough for passage of a pipe to the closet bowl.

3. A wall closet bowl support comprising a base member, a substantially vertical supporting member rising from said base member, said vertical supporting member being bifurcated to provide vertically-extending spaced arms each having a forwardly-extending projection at its upper end.

4. A closet bowl support comprising a base member adapted to be supported by a floor structure, a substantially vertical supporting member rising from said base member and adapted to be located in rear of a bowl, said supporting member having upwardly and forwardly extending spaced arms.

5. In combination, a soil pipe, a closet bowl connected thereto by a flexible connection, and a rigid support for said closet bowl independent of said soil pipe, said support comprising a base and an upright extending from the base and located in rear of the closet bowl.

6. A closet bowl support comprising a horizontally disposed base, an upright extending from said base and rigid therewith, and adapted to be located in rear of a closet bowl, said upright having an attaching part extending forward out of the plane of the upright, the upright also having an opening for passage of a pipe to a closet bowl.

7. A support for a closet bowl comprising

- a horizontally disposed base and an upright rigid with the base, and extending in a general direction vertically from the base, said upright having spaced arms projected laterally out of the plane of the upright. 5
8. In combination, a closet bowl having a substantially vertical rear face, a soil pipe flexibly connected to the bowl, and a support for the bowl comprising a base member 10 adapted to be supported independently of the soil pipe, a supporting member rigid with the base member and extending upward therefrom in rear of said rear face, and means for connecting the bowl to the supporting member, the supporting member being free and disconnected from the soil pipe. 15
9. A support for a closet bowl comprising a horizontal base member, a supporting member integral with and extending vertically from the base, and spaced vertical attaching arms extending forward from said supporting member. 20
10. A support for a closet bowl comprising a base adapted to be supported by a floor structure, an upright rising from said base, and having projections against which the rear of a closet bowl may bear, said upright 25
- also having an opening for passage of a pipe to the said bowl. 30
11. A support for a closet bowl comprising a supporting member adapted to be located in rear of the bowl and having an opening for passage of a pipe to the rear of the bowl, said member having at its upper portion means for attachment to the bowl and at its lower portion a base to support the member independently of said pipe, said member also having a face intermediate the attaching means and the base to engage the bowl. 35
12. A closet bowl support comprising a base member adapted to be supported by a floor structure, an upwardly extending supporting member rising from said base member and adapted to be located in rear of a closet bowl, said supporting member having spaced arms each having a forwardly extending projection at its upper end. 40

In testimony whereof I have hereunto signed my name in the presence of two subscribing witnesses.
